UNITED STATES PATENT OFFICE.

MERRITT W. ALLEY, OF YONKERS, NEW YORK.

CARBURETER.

1,163,581.

Specification of Letters Patent.

Patented Dec. 7, 1915.

Application filed January 28, 1914. Serial No. 814,919.

To all whom it may concern:

Be it known that I, MERRITT W. ALLEY, a citizen of the United States, residing at Yonkers, in the county of Westchester and 5 State of New York, have invented new and useful Improvements in Carbureters, of which the following is a specification.

My invention relates to carbureters adapted for general use, and more particularly 10 to carbureters of the type used in connection with internal combustion engines.

By my invention I seek to accomplish a number of objects, among which are the following: I. To give the carbureting chamber such form as to hasten the thorough commingling of air and vapor. II. To obliterate dead spaces within and immediately adjacent to the carbureting chamber. III. To give the carbureting chamber and parts 20 immediately associated therewith such form as to permit the engine to be effectively throttled down to very low speed and quickly restored to comparatively high speed. IV. To so form the carbureting chamber and the 25 valves partially bounding the same as to properly apportion the richness of the explosive mixture, when the engine is changed from one speed to another. V. To avoid substantial change in the form of the carbureting chamber, while adapting the carbureting chamber for changes in the volume 30 of explosive mixture developed. VI. To spread a given volume of hydrocarbon fuel over a maximum extent of surface and to 35 bring a maximum quantity of air into contact with said surface, in order to attain increased rapidity in vaporization. VII. To liberate the hydrocarbon liquid fuel, within the carbureting chamber, in the form 40 of a very thin film or sheet, so as to increase the surface of the liquid and thus facilitate vaporization. VIII. To bring a volume of air, in the form of a thin layer, into contact with a volume of hydrocarbon 45 liquid fuel, in the form of a thin film or sheet, flowing in a direction crossing the direction of travel of said volume of air, in order to facilitate formation of the explosive mixture.

50 While my invention may be employed in a large number of different relations, and may assume a variety of forms, I will for the sake of conciseness disclose only a single preferred form of the device—it being understood, however, that variations may be 55 made from said form without departing

from the spirit of my invention, which is commensurate with my claims.

Reference is made to the accompanying drawings forming a part of this specification, and in which like letters indicate like parts.

Figure 1 is a side elevation of my carbureter. Fig. 2 is a substantially central vertical section through the same. Fig. 3 65 is a detail view, showing in elevation a part of the means for adjusting the proportion of air and hydrocarbon fuel as supplied to the carbureting chamber. Fig. 4 is a detail view, showing in elevation certain operating 70 arms integral with each other, and parts immediately associated with such arms. Fig. 5 is a plan of a connecting link, used with other parts shown at the top of Figs. 1 and 2. Fig. 6 is a plan view of the improved annular nozzle for discharging the hydrocarbon liquid fuel into the carbureting chamber. Fig. 7 is a view partly in elevation and partly in section, showing further the construction of the nozzle just mentioned, which is made substantially in halves, 80 secured together. Fig. 8 is a plan view of the lower half, or bottom member of the nozzle. Fig. 9 is an inverted plan of the upper half or top member of the nozzle. 85

The float chamber is shown at 10, and contains a float 11, having in this instance a substantially C-form. The float is connected with a float lever 12 which is journaled upon a pin 13 and is connected with a 90 valve 14 for directing the hydrocarbon fuel as supplied into the float chamber. Leading to the valve 14 is a duct 15 with which a fuel connection communicates.

A needle 17 carries a hand wheel 18 95 whereby it is controlled. The upper portion of this needle is threaded, and the needle extends through a suitable mounting 19. Fitted upon the threaded portion of the needle is a lock 20 for securing the needle 100 in the different positions into which it may be moved. Below the lower end of the needle is a valve seat 21, and extending downwardly from this valve seat is a tube 22, open at its lower end in order to admit the 105 liquid. The bottom 23 of the float chamber is provided with a hand valve 24, for the purpose of enabling the float chamber to be readily emptied whenever desired.

The needle 17 and parts immediately associated therewith together constitute a needle valve, and extending from this needle

valve is a tube 25, provided with a small passage 26, and with a threaded portion 27. Engaging this threaded portion is a socket 28, integral with a member 29 of a general 5 annular form, as shown more particularly in Fig. 8. The member 29 is the lower half of a two-part nozzle of annular form, and is provided with an annular bead 30, and with a number of ears 31. The member 10 29 is further provided with a duct 32, which merges into a channel 23 of substantially semi-circular form. Mating the member 29 is another member 34, constituting the upper half of the two-part nozzle. The nozzle member 34 is provided with ears 35 integral with it, and adapted to register with the ears 31, so that the two halves of the nozzle may be secured together by screws 36, as indicated in Fig. 6. To insure accurate fitting of the two halves relatively to each other, the member 34 is provided with an annular step 37 for engaging the annular bead 30, as indicated at the right of Fig. 7. The upper half 34 of the nozzle is further 20 provided with an annular groove 38, this groove being a little deeper at its outer edge than at the inner edge of the annular member in question, so that when the nozzle is assembled, as indicated in Figs. 6 and 7, the 25 groove 38, as bounded in part by the nozzle member 29, presents in cross section a form analogous to a razor blade in cross section. That is to say, the inner edge of the annular groove is very thin, the thickness of the 30 groove gradually increasing toward the outer peripheral edge thereof. The nozzle members 29 and 34 are also provided with annular bevels 39 which converge, and almost meet, where they bound the inner edge 40 of the groove 38, as shown at 40 in Fig. 7.

The annular nozzle as a whole, when placed in position as a part of the carbureter, appears as indicated in Fig. 2, and is encircled by an annular wall 41. Integral 45 with this wall and extending downwardly therefrom is a substantially frusto-conical member 42 provided with a bottom plate 43 of annular form, and connected with this bottom plate is the air pipe 45.

Integral with the annular wall 41 and extending upwardly therefrom is a substantially frusto-conical member 46, having a form quite similar to that of the frusto-conical member 42. These two frusto-conical 50 members are arranged with their apexes toward each other, the inner surface of the frusto-conical members being in registry with the annular beveled surfaces 39 and practically forming continuations of these 55 surfaces.

Between the annular wall 41 and the annular nozzle encircled thereby is an annular space 47, which is idle so far as the active work of the carbureter is concerned, but 60 serves to permit all adjustment between the

annular nozzle and other parts immediately adjacent thereto.

For convenience I designate the frusto-conical members 46 and 42 as the upper and lower cones, respectively.

Fitted upon the upper cone 46 is a cap 48, held in position by bolts 49, and carrying a section 50 of pipe, to be connected with the manifold of the engine. Carried by the cap 48 and extending downwardly therefrom is 70 a sleeve 51. Extending through this sleeve is a tubular valve stem 52, this stem carrying upon its lower end a valve member 53 of conoidal form. Another valve member 54, also of conoidal form, is mounted upon the 80 lower end of a valve stem 55, the latter having in this instance the form of a solid cylindrical rod, which extends entirely through the tubular valve stem 52, in the direction of the axis thereof.

Between the valve members 53, 54, and partly bounded by the annular nozzle above described, is an annular space 56 into which the nozzle is adapted to discharge the hydro-carbon liquid, in the form of a thin film or 90 sheet, the discharge being toward the general axis of the annular nozzle.

Mounted upon the cap 48 and extending upwardly therefrom are two arms 57 which support a bearing shaft 58 of the form 95 shown more particularly in Fig. 3. Encircling this shaft is a sleeve 60. Integral with this sleeve is an arm 61, having the general form of a fork and carrying two pins 62, the latter extending toward each 100 other. Integral with the sleeve 60 and extending upwardly from the same is a bar 63, having a general arcuate form and provided with a slot 64, this slot also having an arcuate form. Extending through the 105 slot 64 is a bolt 65 provided with a lug 66. Encircling the bolt 65, and normally engaging the arm 66 is a bearing sleeve 67. A nut 68 is revolvably fitted upon the bolt 65, which is threaded for this purpose. The operator 110 by turning the nut 68 can loosen the bolt 65 and slide this bolt, together with the lug 66, relatively to the arm 63, and then by tightening the nut 68, can secure the bolt and lug in any one of an infinite number 115 of different positions. A screw 69 extends through the lug 66, and is provided with a head 70 by aid of which it may be turned by hand.

The collar 71, provided with grooves 72 disposed parallel with each other and located upon its opposite sides, is threaded internally and fitted upon the upper portion 120 of the valve stem 55 which is provided with a threaded portion 73 for this purpose. Revolvably fitted upon this threaded portion 73 is a nut 74, serving as a lock for holding the collar 71 rigidly in position relatively to the valve stem 55. By loosening the nut 74 and turning the collar 71, this collar can be

shifted vertically in relation to the valve stem 55, and being then locked by pressure of the nut 74, is incapable of displacement until the nut is again loosened.

5 The tubular valve stem 52 is provided adjacent its upper end with a threaded portion 74, and revolubly fitting upon this portion is a collar 75, similar in form to the collar 71, and similarly provided with 10 a pair of grooves located upon its opposite sides and parallel with each other, as shown at 76. A nut 77, fitted upon the threaded portion 74, is used as a lock for securing the collar 75 in its various 15 positions of adjustment relatively to the threaded portion 74 of the tubular valve stem. Extending into the grooves 76 are two pins 78, which are carried by an arm 79, having the general form of a fork, as will 20 be understood from Fig. 4. The arm 79 is carried by a sleeve 80 with which it is integral, this sleeve being mounted upon a shaft 81. The shaft just mentioned is mounted in bearings 81^a, to which it is connected by aid of pins 82, as may be understood from Fig. 4. Integral with the sleeve 80 and extending outwardly and downwardly therefrom is an arm 83, whereby the engine is controlled—this arm serving the 25 purpose of a throttle lever for controlling generally the admission of air as well as hydrocarbon vapor into the engine manifold.

Carried by the sleeve 80 and integral therewith is an arm 84, having the general 30 form of a fork, as indicated in Fig. 4, and provided with bearings 85. Extending through these bearings is a crank pin 86, held in position by aid of cotter fastenings 87. A pitman 88 (see Fig. 5) is provided 35 at its ends with bearings 89 and 90, the bearing 89 encircling the pin 86, and the bearing 90 encircling the bearing sleeve 67, carried by the arm 63 of arcuate form, as above described.

45 When the arm 83 is turned, the sleeve 80 together with the arms 79 and 84 is rocked. The rocking or angular movement of the arm 79 causes the tubular valve stem 52 to be raised or lowered, and the rocking movement of the arm 84, by shifting the pitman 88 bodily to the right or left, according to 50 Fig. 2, causes the arm 63 to rock, and by so doing the shaft 58 is caused to rock, so that the arm 61 causes the valve stem 55 to be 55 raised or lowered. Each time the arm 83, which serves as a throttle lever, is turned in a clockwise direction, according to Fig. 2, the valve 53 is raised and the valve 54 is lowered so that these valves are thus moved 60 in opposite directions, and away from their respective seats. By adjusting the collar 71 relatively to the valve stem 55, as above described, the valve 54 may be adjusted relatively to the arm 61. Similarly, by ad- 65 justing the collar 75 relatively to the valve

stem 52, the valve 53 may be adjusted relatively to the arm 79. Therefore, assuming that the arms 61 and 79 are in a predetermined relative position, and that the valves 53 and 54 are in engagement with their seats respectively, either valve may be moved slightly away from its seat, and thus given more or less lead relatively to the other valve, by appropriate adjustment of the collar 71 or 75. Except for purposes of giving either of the valves 53 and 54, the above mentioned lead over the other, and for making adjustment of the various movable parts in assembling the device, or for making adjustments necessitated by climatic conditions, the collars 71 and 75 are seldom or never shifted relatively to the valve stems with which they are connected.

In order to change or adjust the ratio of air and vapor supplied to the engine, use is 35 made of the screw 69. By turning this screw in one direction the adjacent end of the pitman 88 is lowered, and by turning the screw in the opposite direction, said adjacent end of the pitman is raised. The arm 84 being 40 of a constant length, and the virtual length of the arm 63 being adjustable by aid of the screw 69 in the manner just described, the relative positions of the valve stems 52 and 55, and consequently the relative positions of the valves 53 and 54, are rendered 45 adjustable. By thus using the screws 69 for purposes of adjustment, the richness of the explosive mixture may be regulated to 50 nicety, at the will of the operator.

The arm 83 is the controlling arm—or, practically speaking, the throttle lever of the engine, is turned in a clockwise direction according to Figs. 1 and 2, in order to supply 55 the explosive mixture to the engine, the degree of rotation of the arm in question governing the quantity of the mixture supplied. When the arm is rotated in a contra-clockwise direction to the limit of its travel—that is, until at least one, and usually both, 60 of the valves 53 and 54 are seated, the engine is no longer supplied with the mixture, or at least with both air and vapor.

While for convenience I designate the frusto-conical members 53 and 54 as valves, 65 they have each the function of a deflecting plate, in that each of them serves as a spreader for the aeriform material passing around it. Owing to the frusto-conical form of these valves and their seats, the valves when moved slightly from their 70 seats are yet concentric thereto, and between each of the valves and its seat, there is formed an annular passage of substantially frusto-conical form. The arrangement of the parts is such that when a partial vacuum is created within the pipe 50, and consequently the explosive mixture is forced upwardly through the annular passage between the valve 53 and its seat, the 75

partial vacuum is slightly greater in the upper part of this annular passage than in the lower portion thereof. This is due to one of the well known principles of aspiration. In consequence of the greater rarefaction of the explosive mixture as it travels upward, the upper portion of the annular passage in question facilitates the evaporation of any finely divided portion of hydrocarbon liquid carried up by the travel of the mixture.

Most of the movable parts above described are neatly balanced, so that the parts are maintained as nearly as practicable in equilibrium at all times, and when such parts are moved, a minimum of energy is required for this purpose.

The operation of my device will readily be understood from the foregoing description.

The various parts being assembled and arranged, as described, and the adjustable parts having been properly adjusted, the suction draft of the engine produces a partial vacuum in the pipe 50. Air is drawn through the pipe 45, and passes upwardly between the valve 54 and its seat. Hydrocarbon fuel, driven by atmospheric pressure, is discharged from the annular groove 38, in the form of a very thin sheet or film, the direction of travel of the same being toward the vertical axis of the annular nozzle. Inflowing air passes at substantially a right angle directly across the general plane of the film or sheet of hydrocarbon liquid, and in very close contact therewith. Owing to the form of the parts here under discussion, a given volume of hydrocarbon liquid and a given volume of air are brought into such intimate and thorough contact that the vaporization of the liquid, and the thorough admixture of the resulting vapor, and the volume of air is greatly facilitated, and the process correspondingly quickened. In this connection it should be borne in mind that the annular nozzle shown in Figs. 6, 7, 8 and 9 has a comparatively large internal diameter, or in other words that the groove 38 is of considerable length. This means, in effect, that the flow of air, in the form of a comparatively thin layer, takes place directly across the edge of a very thin sheet of volatile hydrocarbon liquid, said sheet being of a considerable width. Such being the case, not only is the vaporization complete, but the admixture of the vapor and the air is accomplished thoroughly and in a relatively short time.

I do not limit myself to the precise construction shown, as variations may be made therein without departing from the spirit of my invention.

I claim:—

1. In a carbureter, the combination of an annular nozzle, provided with an endless

groove gradually tapering in thickness from its outer edge to its inner edge, said inner edge being flush with the inner surface of said annular nozzle, means for admitting a hydrocarbon liquid into said nozzle so as to discharge said liquid from the thin edge of said annular groove, a substantially frusto-conical member having its apex end abutting against said annular nozzle, a deflector mounted within said substantially frusto-conical member, and means controllable at the will of the operator for adjusting said deflector bodily in relation to said frusto-conical member.

2. In a carbureter, the combination of a carbureting chamber provided with frusto-conical members, an annular nozzle located between said portions of large diameter for the purpose of discharging a hydrocarbon liquid, a deflector mounted within each of said frusto-conical members, a stem connected with each of said deflectors, an arm connected with each of said stems, a rocking shaft for supporting each of said arms, a second arm carried by each rocking shaft, a pitman pivotally connected at one of its ends to one of said last mentioned arms, and means controllable at the will of the operator for adjustably connecting the opposite end of said pitman with the other of said last mentioned arms.

3. In a carbureter, the combination of an annular nozzle provided internally with an annular groove for discharging a hydrocarbon liquid, a substantially frusto-conical member having its apex end connected with said nozzle, a deflector of substantially frusto-conical form located within said frusto-conical member and concentric thereto, a stem connected with said deflector, a collar carried by said stem, means controllable at the will of the operator for adjusting said collar into different positions relatively to said stem, a rocking arm connected to said collar for the purpose of actuating said stem, and means controllable at the will of the operator for adjusting said rocking arm into different angular position.

4. In a carbureter, the combination of a carbureting chamber provided with substantially frusto-conical portions having their apex ends extending toward each other, a nozzle of substantially annular form located between said frusto-conical members, a pair of deflectors each of frusto-conical form, each deflector being disposed within one of said frusto-conical members, a stem connected with each deflector, a rocking arm connected with each stem, means for adjusting each stem relatively to the rocking arm with which it is connected, and means controllable at the will of the operator for adjusting said rocking arms into relatively different angular positions.

5. In a carbureter, the combination of a

carbureting chamber provided with two portions each of substantially frusto-conical form, a pair of deflectors each located within one of said portions, means for admitting air directly into one of said portions, means for maintaining a partial vacuum in the other of said portions, an annular nozzle between said portions for the purpose of discharging a hydrocarbon liquid, and mechanism con-

trollable at the will of the operator for adjusting one of said deflectors independently of the other, relatively to said frusto-conical members. 10
